UNITED STATES PATENT OFFICE

ERNEST BERGMAN, OF LONG BEACH, CALIFORNIA

DESIGN FOR A BOOKMARKER

Application filed September 23, 1930. Serial No. 37,059. Term of patent 3½ years.

To all whom it may concern:

Be it known that I, ERNEST BERGMAN, a citizen of the United States, and a resident of Long Beach, in the county of Los Angeles and State of California, have invented a new, original, and ornamental Design for a Book Marker, of which the following is a specification, reference being had to the accompanying drawings, forming a part thereof.

I claim:

The ornamental design for a book marker, substantially as shown.

In testimony whereof, I affix my signature.

ERNEST BERGMAN.
